CLAIM

U.S. PATENT DOCUMENTS

The ornamental design for a brush, as shown and described.

2,006,234 A	*	6/1935	Cosby	.....	15/143.1
2,090,050 A	*	8/1937	Jackson	.....	601/154
3,597,098 A	*	8/1971	Kellis	.....	401/6
D266,116 S		9/1982	Deconinck		
D326,778 S		6/1992	Vetter		
D362,965 S		10/1995	Tastanis		
D438,013 S		2/2001	Hay		

DESCRIPTION

FIG. 1 is a front perspective view of the brush;

FIG. 2 is a top plan view of the brush;

FIG. 3 is a side elevation view of the brush, the other side views being identical; and,

FIG. 4 is a bottom plan view of the brush.

The broken-line showing of the brush bristles is environmental structure and for illustrative purposes only and forms no part of the claimed design.
